UNITED STATES PATENT OFFICE.

ERIK L. KRAM, OF CHICAGO, ILLINOIS, ASSIGNOR TO KRAM IMPERIAL CABINET COMPANY, A CORPORATION OF ILLINOIS.

METALLIC FILING-CASE.

No. 798,514.

Specification of Letters Patent.

Patented Aug. 29, 1905.

Application filed November 1, 1902. Serial No. 129,779.

To all whom it may concern:

Be it known that I, ERIK L. KRAM, a citizen of the United States, residing at Chicago, in the county of Cook and State of Illinois, have 5 invented certain new and useful Improvements in Metallic Filing-Cases, of which the following is a specification.

The object of this invention is the production of a metallic filing-case having vertically- 10 adjustable shelves, with a secure and convenient means for supporting and changing the position of said shelves.

The invention further has regard to the general construction and arrangement of the 15 parts of a filing-case.

In the accompanying drawings, Figure 1 is a front elevation of a filing-case embodying the features of my invention. Fig. 2 is a transverse vertical section on dotted line 2 2 20 of Fig. 1. Fig. 3 is a horizontal section on dotted line 3 3 of Fig. 1. Fig. 4 is a top plan view of one of the shelves in the lower part of the case.

This improved cabinet comprises a base A, 25 sides B, a back C, and a top D. Two vertical supporting-bars E are secured to the inner faces of the sides B at a little distance from their forward edges and slightly offset from said sides. These vertical supporting-bars 30 have oblique notches or pockets E' for supporting the shelves, as will hereinafter more fully appear. The inner faces of the back C are also provided with two vertical supporting-bars F, having openings F', lying in the 35 same horizontal plane with the lower portion of the pockets E', intended for supporting the same shelf.

Two forms of shelf are provided—one, G, for supporting books (illustrated in Fig. 3) 40 and the other, H, for supporting drawers. Each of the shelves G is provided with an outer rectangular framework G', having a rectangular reentrant portion G² in said framework, providing an opening for the hand of 45 the person taking a book from the shelf. Rollers G³ are provided, upon which the book rests and which rotate to permit it to be slid easily into place upon the shelf. Studs G⁴

project outwardly from opposite sides of the framework and are adapted to enter the 50 oblique pockets E'. Two other studs G⁵ project rearwardly from the shelf G in position to enter the openings F' of the vertical supporting-bar F, the shelf being supported upon said studs G⁴ and G⁵, lying in the pockets E' and F', respectively. 55

The shelf H comprises a sheet-metal top H', bent at its forward and rear edges over rods H² and H³. The ends of the rod H² at the forward edge of the shelf project from each side 60 of the top H' thereof a sufficient distance to enter the oblique pockets E' and support the forward edge of the shelf. Studs H⁴ are secured to the rear rod H³ in proper position to enter the openings F' in the vertical bars F 65 and support the rear edge of the shelf.

The shelves are withdrawn by raising the forward edge and withdrawing the studs G⁴ (or the ends of the rod H² in the case of the shelf H) from the pockets E'. This pulls the 70 shelf forward and withdraws the studs G⁵ (or those H⁴) from the openings F' in the vertical supporting-bars F. The shelves may be placed at any desired distance apart within the range of adjustment of the case. 75

It is apparent that the filing-case herein described may be made of sufficient width to accommodate two or more tiers of shelves, supporting-bars being provided between adjacent tiers, that the rear supporting-bar may be 80 provided with notches or projections for holding the rear edges of the shelves, and that many other changes may be made without departing from the spirit and scope of my invention. I therefore desire to have it understood that I do not limit myself to the precise 85 details herein set forth.

I claim as my invention—

In a filing-cabinet, in combination, a casing comprising two sides and a back; a single vertical supporting-bar secured to the inner face of each of said sides near the forward edge thereof, said bars having therein a series of oblique pockets opening toward the forward side of the cabinet; two vertical supporting- 95 bars spaced apart and secured upon the inner

face of said back, said bars having therein a series of openings vertically alined with the pockets of the side supporting-bars; and a shelf having upon each of its ends near its forward edge a stud adapted to lie in the pockets of the side supporting-bars and having upon its rear side two studs adapted to lie

within the openings in the supporting-bars secured to the back.

ERIK L. KRAG.
